Attorney

UNITED STATES PATENT OFFICE.

HARRY LAVON BISHOP, OF ARCADIA, FLORIDA.

RIVETING TOOL.

Application filed March 7, 1925. Serial No. 13,881.

To all whom it may concern:

Be it known that I, HARRY LAVON BISHOP, a citizen of the United States, residing at Arcadia, in the county of De Soto and State 5 of Florida, have invented a new and useful Riveting Tool, of which the following is a specification.

This invention relates to the riveting tool and more particularly to a tool of this kind 10 used in connection with hollow or split rivets.

The object of the invention is to provide a simple, strong, cheap structure for use in riveting small work such as relining transmission bands and the like, and which may 15 be quickly and easily operated with a minimum exertion of force.

With the foregoing and other objects in view which will appear as the description 20 proceeds, the invention resides in the combination and arrangement of parts and in the details of construction hereinafter described and claimed, it being understood that changes in the precise embodiment of the invention herein disclosed may be made within 25 the scope of what is claimed without departing from the spirit of the invention.

In the accompanying drawings:—

Fig. 1 represents a side elevation of 30 a tool constructed in accordance with this invention;

Fig. 2 is a top plan view thereof;

Fig. 3 is a rear elevation with the handle or operating lever shown in section;

Fig. 4 is a front elevation thereof with parts broken out; and

Fig. 5 is a perspective view showing a punch for use in connection with the riveting apparatus with the parts thereof arranged in juxtaposition ready for assembling.

The tool constituting this invention comprises a supporting frame made in the form of a base 1 preferably constructed of a 45 heavy metal bar and a top member 2 of a corresponding shape and size spaced vertically above the base and supported by standards arranged in pairs at the rear end and the center of the frame such standards being numbered 3 and 4 and 5 and 6 respectively. The intermediate standards 5 and 6 are longer than those at the rear of the

frame and extend above the top bar 2 having their ends converging and form a support for a beam 7 which is fulcrumed intermediate its ends between the upper ends of the standards 5 and 6.

A plunger 8 extends loosely through the rear end of the top bar 2 with its upper end located directly beneath the rear end of beam 7 and its lower end rests on the front end of a lever 10 which is fulcrumed between the standards 3 and 4 about midway the length of said standards. The lever 10 projects some distance to the rear of the 60 supporting frame and may be of any desired length according to the leverage desired for operating the tool.

Another plunger 11 is mounted to reciprocate in the front end of bar 2 and is provided at its upper end with a bifurcated detachable head 12 between the furcations 13 of which the front end of beam 7 is mounted and which is held engaged with said beam by means of a coiled spring 14. Another coiled spring 15 encircles the plunger 11 below the bar 2 and bears at one end against 65 said bar and at the other against a collar 16 fixed to the plunger, and which operates to retard the upward movement of the 70 plunger.

A pair of spring fingers 17 and 18 depend from collar 16 at diametrically opposite sides thereof and have their free ends bent inwardly to form clamps for securing the rivets in connection with which the tool is to be used. The lower end of the plunger 11 is reduced to form a rivet engaging hammer 19 located between the inturned ends of the fingers 17 and 18 as is shown clearly 85 in Fig. 1. A die 20 is fixed to the base of this tool to cooperate with the plunger in riveting.

In the use of this tool the rivet is placed with the head gripped between the fingers 90 95 17 and 18 and abutting against the reduced plunger end 19 and when inserted between the goods to be secured it is located directly over the die 20. The lever 10 is then lowered into the dotted line position shown in Fig. 1 100 which elevates plunger 8 and thus forces the rear end of the beam 2 up and its front end down causing the plunger 11 to be depressed against the tension of its spring 14 thus

forcing the rivets into operative clinching position. When pressure on the lever 10 is released the coiled spring 14 will operate to raise the front ends of the beam 7 and therefore by force the rear end down causing the rear plunger 8 to move downwardly against the front end of lever 10 and hold it in the position shown in full lines in Fig. 1 ready for the next operation.

10 The head 12 of the front plunger 11 being removable different forms of plungers may be substituted for that shown at 11 and in Fig. 5 a punch 21 is shown having a reduced threaded upper end 22 for engagement with the head 12 and at its lower end is equipped with a punching die 23 designed to enter socket 24 in a die 25 which is substituted for the die 20 when the punch 21 is used.

15 20 I claim:—

1. A riveting tool comprising a supporting frame, a spring retracted plunger mounted to reciprocate therein and having means for holding the rivets to be set, a beam 25 fulcrumed on said frame with one end engaging said plunger, another plunger engaging the other end of said beam, and a lever for actuating said last mentioned plunger to operate the beam and actuate the 30 spring pressed plunger.

2. In a tool of the class described, a supporting frame, a beam fulcrumed intermediate its ends on said frame, a spring pressed plunger located below one end of said beam 35 and engaged therewith, a freely movable plunger located beneath the other end of said beam, rivet carrying means on the spring pressed plunger, and a lever fulcrumed in said frame with one end engaging 40 the freely movable plunger whereby the actuation of the lever will operate the beam

to depress the spring pressed plunger against the tension of its spring.

3. A riveting tool comprising vertically spaced bars, standards straddling and connecting said bars, plungers mounted in the opposite ends of the upper bars, one of said plungers being spring retracted and provided at its lower end with rivet holding fingers, the upper end of said plunger being bifurcated, a beam fulcrumed on one pair of said standards and having one end engaged with the furcations of the plunger and its other end supported by the other of said plungers, and a lever fulcrumed between two of said standards and having one end engaged with the last mentioned plunger whereby the operation of the lever will actuate the beam to depress the spring projected plunger against the tension of the spring.

4. In a tool of the class described a supporting structure, plungers mounted to reciprocate in said structure, a beam fulcrumed intermediate its ends and supported at its end by one of said plungers, the other of said plungers having a detachable bifurcated head engaged with said beam and provided with a coiled spring to normally move the beam upward and retract the plunger, spring fingers carried by said last mentioned plunger for holding the rivets to be riveted, and a lever engaging the other plunger whereby the lowering of the lever will operate to elevate one end of the beam and lower the other thereby forcing the spring pressed plunger downward into operating position.

In testimony that I claim the foregoing as my own, I have hereto affixed my signature.

HARRY LAVON BISHOP.
